Primary Examiner — George A Bugg*Assistant Examiner* — Tamara L Hahn(74) *Attorney, Agent, or Firm* — Bush Intellectual Property Law; Kenneth M. Bush(57) **CLAIM**

I claim the ornamental design for a floating basket, as shown and described.

DESCRIPTION

FIG. 1 is a top, front, left side perspective view of a floating basket showing my new design;

FIG. 2 is a top, rear, right side perspective view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a left side elevational view thereof; the right side elevational view being a mirror image of the left side elevational view.

The broken lines shown in the figures represent portions of the floating basket that form no part of the claimed design.
